DRY CLEANING COMPOSITIONS

Raymond L. Mayhew, Phillipsburg, and John P. Miller III, Bloomfield, N.J., and Marvin Kopp, Lenox, Mass., assignors to General Aniline & Film Corporation, New York, N.Y., a corporation of Delaware
No Drawing. Filed Jan. 11, 1957, Ser. No. 633,545
6 Claims. (Cl. 252—152)

This invention relates to improvements in the dry cleaning of fibrous textiles and related materials and more particularly to new and improved compositions for use with dry cleaning solvents, and to processes of dry cleaning wherein said improved compositions are employed.

It is well known that many types of fabrics and materials cannot be cleaned by the ordinary means of soap or detergents and water, such as are employed in laundering type operations since the presence of water deleteriously affects such materials. To provide effective cleaning for such materials, a dry cleaning process must be used. Dry cleaning processes employ organic solvents which are effective in removing from the materials treated most of the undesirable dirt, grease, dust and the like. It is also a common expedient in dry cleaning processes to add a small amount of water which, sufficiently dispersed in the dry cleaning fluid, will be effective to remove water-soluble stains without adversely affecting the material treated.

It is therefore an object of this invention to provide new compositions, particularly suitable for use in dry cleaning operations.

It is a further object of this invention to provide new compositions suitable for use in all of the generally employed dry cleaning solvents.

It is a still further object of this invention to provide new compositions which give outstanding and improved cleaning ability by virtue of an outstanding detergency action coupled with an excellent ability to prevent soil redeposition on the materials treated.

It is another object of this invention to provide an improved process of dry cleaning in all types of dry cleaning solvents.

It is a further object of this invention to provide an improved process of dry cleaning wherein the usual dry cleaning solvents are employed in conjunction with minor amounts of water.

According to the present invention the new compositions thereof, hereinafter termed dry cleaning compositions, to be incorporated in the usual dry cleaning solvents contain as the essential components thereof a cationic surfactant derived from fatty amines and an alkylene oxide and at least one anionic surfactant. In addition thereto it is desirable to incorporate in the above described mixture an additional surfactant of the nonionic type.

Compositions as above described give particularly outstanding results in all types of dry cleaning solvents. In addition, they give excellent results where a small amount of water has been incorporated into the dry cleaning solvent for the purposes described above. Among the dry cleaning solvents one may use and which are normally employed in dry cleaning operations are the following:

Gasoline
Kerosene
Trichloroethylene
Tetrachloroethylene
Carbon tetrachloride
Stoddard solvent, and the like

The cationic agents which are contemplated in this invention are derived as described above from fatty amines reacted with alkylene oxides or their equivalent. The fatty amines which are employed herein are those amines which contain at least 75% unsaturated linkages therein,

2

of which at least 35% are of the double unsaturated type. Since such amines are usually obtained from natural fatty oils, they are usually employed as mixtures, which mixtures correspond to the composition of the naturally occurring oils. Thus, an outstanding and preferred amine identifiable as a soybean amine is derived from the soybean oil fatty acids by ammonolysis and reduction to give a mixture of amines of the following approximate composition:

	Percent
Octadecadienyl amine	45
Octadecenyl amine	35
Octadecyl amine	10
Hexadecyl amine	10

15 It will be noted that this mixture contains 80% unsaturates of which 45% are of the diethenoid type. It is of course possible to employ in the preparation of the compositions of this invention synthetically prepared mixtures from the various amines within the scope of this invention and it 20 is further possible to employ the pure unsaturated amines provided they come within the scope of the above limitations. In addition to soybean amine, numerous other fatty oils are suitable as precursors for the amines operable in this invention. Such fatty oils include cottonseed oil, corn oil, sesame oil, sunflower seed oil and the like. The approximate acid constituents of these oils are 25 given below:

	Percent
Linoleic acid	51
Oleic acid	24
Saturated acids	25

Cotton seed oil

	Percent
Linoleic acid	39
Oleic acid	43

Unsaturated acids and neutral materials Remainder

Corn oil

	Percent
Linoleic acid	35

Oleic acid Remainder

Saturated acids and neutral materials Remainder

Sesame oil

	Percent
Linoleic acid	46

Oleic acid Remainder

Saturated acids and neutral materials Remainder

Sunflower seed oil

	Percent
Linoleic acid	57

Oleic acid Remainder

Saturated acids and neutral materials Remainder

50 Amines derived from these oils in the manner of that described above for soybean amine will contain at least 75% of the amine constituent as unsaturates of which amount at least 35% will represent doubly unsaturated compounds. In addition to the above mentioned fatty 55 oils it is also possible to employ other naturally occurring materials which, upon suitable treatment by hydrolysis, ammonolysis and reduction, yield an amine or mixtures of amines coming within the scope of the limitations described above as to the unsaturation content thereof. The

60 cationic agent suitable for use in the compositions of this invention are prepared from the above described amines or mixtures of amines by well known reactions with alkylene oxides or their equivalents. The polyoxyalkylated products resulting from such processes which are suitable 65 for use in this invention are those products which contain from about 14 to about 53% alkylene oxide or its equivalent (1 to 7 moles of alkylene oxide per mole of amine). Methods for the preparation of such condensation products are described in United States Patents 1,970,578 and 2,213,477.

70 The anionic synthetic surfactant to be employed as the second component of the compositions of this invention

include the alkyl aryl sulfonates such as sodium keryl benzene sulfonate, diisobutyl naphthalene sulfonic acid and the like, the N-fatty acid acyl-N-alkyl taurates, such as sodium-N-oleoyl-N-methyl taurate, sodium-N-lauryl-N-cyclohexyl taurate, and the like, alkyl aryl-polyoxyalkylene salts such as those derived from alkylated aromatic hydroxy compounds of the benzene and naphthalene series reacted with 3 to 7 moles of an alkylene oxide or its equivalent and subsequently esterified with a strong acid such as sulfonic, phosphoric or the like. Additionally, anionic salts from the nonionic alkyl aryl polyoxyalkylene glycols described below may be employed.

In addition to the two classes of ingredients described above, that is, the cationic and anionic surfactants, there may be employed in the composition a nonionic surfactant of the alkyl aryl polyoxyalkylene glycol type. These glycol ethers may be derived in the known manner from alkylated aromatic hydroxy compounds of the benzene and naphthalene series such as p-n-butylphenol, amylocresol, diisobutylphenol, diamylphenol, isoheptylphenol, oleylphenol, isododecylphenol, tetradecylphenol, isoctylresorcinol, nonylphenol, dinonylphenol, isoocetylphenol, isoctyl- β -naphthol, isoheptylxylenol, n-octadecylphenol, and the like. In general, these alkylated aromatic hydroxy compounds should contain at least one alkyl radical of at least 4 carbon atoms as a ring substituent. It will be understood that such compounds may contain up to 3 alkyl substituents which may be straight or branched, which substituents may contain a total of 20 or more carbon atoms.

These alkylaryl hydroxy compounds are polyoxyalkylenated by reaction under proper conditions, preferably in the presence of an alkaline catalyst such as potassium hydroxide or sodium hydroxide, and heat and pressure, with from 3 to 7 moles of an alkylene oxide such as ethylene oxide, propylene oxide, or the like, or mixtures thereof.

The anionic polyoxyalkylene salts described above are readily prepared from these nonionic compounds by subjecting said nonionic glycol ether to esterification with a strong acid such as chlorosulfonic, sulfamic, sulfuric, or phosphoric or with an inorganic acid anhydride such as sulfur trioxide or phosphorus pentoxide or with acid halides such as sulfuryl chloride, phosphorus oxychloride or phosphorus pentachloride or the like. When a properly substituted acid mixture is employed in the esterification such as aminosulfonic acids, sulfamic acid, ammonium bisulfate, and the like, a water-soluble or dispersible salt is directly produced without the necessity of subsequent neutralization with a basic substance. In such cases, subsequent treatment with basic materials is only for the purpose of neutralizing excess acid, and the like. Excellent results are also obtained when complexes of some of the above acids and anhydrides are employed. For example, a combination of sulfur trioxide or chlorosulfonic acid with an ether such as dioxane, thioxane or β,β' -dichlorodiethyl ether, or with a tertiary nitrogen base such as pyridine or triethylamine may be used. The resulting esters may be neutralized with a basic material such as sodium hydroxide, potassium hydroxide, sodium carbonate, sodium acetate, ammonium hydroxide, ammonia, calcium oxide and hydroxide, magnesium oxide and hydroxide, strontium hydroxide, ethanolamine, diethanolamine, triethanolamine, methylamine, dimethylamine, trimethylamine, ethylamine, triethylamine, diethylamine, butylamine, propylamine, cyclohexylamine, morpholine, pyridine, octanolamine, octylamine, and the like.

The greatest values to be derived from this invention lie not only in the superior detergent action of the dry cleaning compositions thereof but further, in the outstanding characteristics of soil redeposition prevention and whiteness retention which are evident in all types of dry cleaning solvents. This is in contrast to the usual detergent compositions which are suitable for use in only

one of the two major types of dry cleaning solvent systems. In order to achieve the excellent and superior effects to be derived from the use of the compositions of this invention, the proportions of the various ingredients thereof must be employed within certain critical limits. The cationic surfactant which, as described above, is of the polyoxyalkylated unsaturated amine type, should comprise at least 25% on a volume basis of the total surfactants present, and no more than about 55%. The above described anionic agents should be employed within the range of 30 to 75% on a volume basis based on the total surfactants present. The nonionic compounds when present should not exceed on a volume basis 30% of the total surfactants. While it is not essential in order to achieve outstanding results with the compositions of this invention to incorporate a nonionic agent in the majority of formulations, the addition thereto of nonionics results in compositions of exceptionally outstanding properties. The formulations hereinafter described where specific data is indicated for detergency action and whiteness retention characteristics were tested as follows:

Into each of 8 pint Mason jars there were introduced—
50½ in. steel balls
50 ml. of solvent
1 3½ in. diameter circular swatch of acetate jersey or Botany wool flannel, soiled or unsoiled, as indicated below.

The 8 jars contained the following:

TABLE 1
Launder-Ometer test components

Jar No.	Test
35	
1	Acetate jersey soiled swatch.....
2	Wool flannel soiled swatch.....
3	Acetate jersey soiled swatch, detergent wet stock.
4	Wool flannel soiled swatch, detergent wet stock.
5	Unsoiled acetate jersey swatch, 5 mg. synthetic dry soil.
6	Unsoiled acetate wool flannel swatch, 5 mg. synthetic dry soil.
7	Unsoiled acetate jersey swatch, 5 mg. synthetic dry soil, detergent wet stock.
8	Unsoiled wool flannel swatch, 5 mg. synthetic dry soil, detergent wet stock.

The synthetic dry soil used in the above tests has the following composition:

TABLE 2
Synthetic soil composition
Ingredients mixed as follows:

Components	Percent	Grams
55 hyperluminus cement—Alpha Type I.....	34.65	34.4
SiO ₂ (gel-200 mesh, Davyson).....	15.00	15.0
Avery Clay (Harris Clay Co.).....	15.00	15.0
gelatin (Keystone 431X).....	3.50	3.5
NaCl (C.P. grade).....	5.00	5.0
Fe ₂ O ₃ (C. K. Williams).....	0.25	2.4
carbon black (Mallacco).....	1.50	15.0

The above were mixed in a ball mill until heterogeneous. The oils listed below were melted and blended by hand into the powdered mixture. They were:

Components	Percent	Grams
stearic acid.....	1.6	16.0
oleic acid.....	1.6	16.0
palm oil fatty acid (Harsborn).....	3.2	32.0
lauryl alcohol.....	0.5	5.0
lanolin anhydride (Merck).....	1.0	10.0
in-octadecane (Conn. Hard Rubber).....	1.1	11.0
1-octadecene (Humphrey Wilkinson).....	1.1	11.0

1500 ml. H₂O were added. The above were mixed in a ball mill for 16 hours and dried. The dried soil was then

pulverized in a hammer mill to approximately 200 mesh.

The cloth used for detergency tests was soiled by padding in the Butterworth three-roll padder, giving 3 passes through a 5% suspension of the synthetic dry soil in Stoddard solvent and air drying the cloth. All cloth was stored in a constant humidity chamber prior to use at a relatively humidity of 50 to 63%.

The test conditions were as follows:

Apparatus employed: Atlas Launder-Ometer (42 r.p.m.) with water bath drain to avoid excess moisture

Temperature: Temperature maintained at room temperature

Medium: Stoddard solvent or perchlorethylene—50 cc.

Cleaning cycle: 15 min.

Rinse cycle: 15 min., in 50 cc. clean solvent

Control: Appropriate solvent with no detergent added

In the following examples which will serve to exemplify the compositions and processes of this invention, it will be understood that such exemplification is not deemed to be limitative of the invention herein covered. In the

reacted with 33% ethylene oxide are added to 10 parts of Stoddard solvent (a petroleum solvent). The efficiency of the above formulation is set forth in Table 3 and a comparison with other commercial dry cleaning detergents and a control containing no detergent is also given.

In the following table, column 1 indicates the detergent tested, column 2 the fabric, which is prepared for the detergency tests as described above. Column 3 lists the solvents employed, column 4, the detergency efficiency where one is employed, based on reflectance readings. The standard is taken as a magnesium oxide block=100. The unsoiled rayon and wool have varying degrees of whiteness and therefore the significant values are the differences appearing in columns 5 and 7. Thus the larger the value in column 5 the better is the cleaning action of the composition. The smaller the figure in column 7 the better is the composition for preventing soil redeposition. The figures in column 6(a) are the values obtained for unsoiled, untreated fabrics, those of column 6(b) the values for the same swatches put through a cleaning cycle as indicated in Table 1 for jars 5-8.

¹ Acetate jersey.

² Wool flannel.

³ Stoddard solvent.

⁴ Perchloroethylene.

^{5, 6} Useful only in solvent tested.

⁷ The "cleaned" wool was not cleaned in this test.

⁸ Fabric badly streaked.

^{9, 10, 11, 12} These agents useful only in the solvents tested.

said examples, parts indicates parts on a volume basis unless otherwise indicated.

EXAMPLE 1

A mixture of 7½ parts diisobutyl naphthalene sulfonic acid and 2½ parts of a cationic surfactant prepared from refined soybean amine having the following composition:

	Percent
Octadecadienyl amine	45
Octadecenyl amine	35
Octadecyl amine	10
Hexadecyl amine	10

From the data in the above table it is evident that the composition of Example 1 is an excellent detergent for both rayon and wool with outstanding whiteness retention characteristics. Further, this composition is useful in both types of dry cleaning solvents normally used which is not so of the commercial agents tested. It should be further noted that a large value in column 5 is not per se indicative of outstanding detergency action since this figure must be compared to the control, i.e., solvent without detergent. Thus, the composition of Example 1 when tested in Stoddard solvent on rayon

gives a value of 14.6 in column 5 as opposed to a value of 2.0 for the control. Commercial agent D with rayon, on the other hand, gives a value of 29.4 but this must be compared to the control value of 29.7 which indicates that here the detergent impaired the normal action of the solvent.

EXAMPLE 2

A composition comprising the following ingredients is prepared:

Components:	Parts by volume
Alkylaryl polyoxyethylene glycol ¹	3.0
Reaction product of refined soybean amine containing 33% ethylene oxide	4.0
Diisobutyl naphthalene sulfonic acid	1.5
Alkylaryl polyoxyethylene sulfate ²	1.5
Petroleum solvent	5.0

¹ Nonyl phenoxy polyoxyethylene ethanol (58% ethylene oxide).

² Ammonium salt of the sulfate ester of nonyl phenoxy (58% ethylene oxide).

EXAMPLE 3

A composition comprising the following ingredients is prepared:

Components:	Parts by volume
Alkylaryl polyoxyethylene glycol ¹	3.0
Reaction product of refined soybean amine containing 33% ethylene oxide	4.0
Sodium keryl benzene sulfonate	3.0
¹⁰ Nonyl phenoxy polyoxyethylene ethanol (58% ethylene oxide).	

The results are given in Table 4.

EXAMPLE 4

A composition comprising the following ingredients is prepared:

Components:	Parts by volume
Sodium N-oleoyl-N-methyltaurate	5
Reaction product of refined soybean amine containing ethylene oxide (33%)	6
n-Butanol	1
Petroleum solvent	4

The results are given in Table 4.

¹ A is reaction product showing refined soybean amine containing 33% ethylene oxide.

² B is reaction product showing refined soybean amine containing 14% ethylene oxide.

³ C is reaction product showing refined soybean amine containing 53% ethylene oxide.

⁴ D is diisobutyl naphthalene sulfonic acid.

⁵ E is sodium keryl benzene sulfonate.

⁶ F is sodium N-oleoyl N-methyl laurate.

⁷ G is nonyl phenoxy polyoxyethylene ethanol.

employed. In each instance the results are outstanding in so far as detergency action is concerned and further, there is excellent soil redeposition prevention.

This invention has been disclosed with respect to certain preferred embodiments. Various modifications and variations of these embodiments will become apparent to those skilled in the art, and it is to be understood that such modifications and variations are to be included within the spirit and purview of this application and the scope of the appended claims.

We claim:

1. A composition adapted for use in the dry cleaning of textile and fibrous materials consisting essentially of a surface active agent mixture for each 100 parts of which there are present at least 25 parts of a polyoxyalkylated dialkenoid fatty amine containing from about 14 to about 53% alkylene oxide and 30 to 75 parts of an anionic surface active agent.

2. A composition adapted for use in the dry cleaning of textile and fibrous materials consisting essentially of a surface active agent mixture for each 100 parts of which there are present at least 25 parts of a polyoxyalkylated dialkenoid fatty amine containing from about 14 to about 53% ethylene oxide and 30 to 75 parts of an anionic surface active agent selected from the group consisting of alkylaryl sulfonate surface active agents, N-fatty acid acyl-N-alkyl taurate surface active agents and alkylaryl polyoxyalkylated salt surface active agents and mixtures thereof.

3. A composition adapted for use in the dry cleaning

of textile and fibrous materials consisting essentially of a surface active agent mixture for each 100 parts of which there are present at least 25 parts of polyethoxylated soybean amine containing from about 14 to about 53% ethylene oxide, and 30 to 75 parts of an anionic surface active agent selected from the group consisting of alkylaryl sulfonate surface active agents, N-fatty acid acyl-N-alkyl taurate surface active agents and alkylaryl polyoxyalkylated salt surface active agents and mixtures thereof.

10 4. A composition as defined in claim 3 wherein the anionic surface active agent is diisobutyl naphthalene sulfonic acid.

15 5. A composition as defined in claim 3 wherein the anionic surface active agent is a mixture of diisobutyl naphthalene sulfonic acid and an alkylaryl polyoxyethylene sulfate.

6. A composition as defined in claim 3 wherein the anionic surface active agent is sodium N-oleoyl-N-methyl taurate.
